UNITED STATES PATENT OFFICE

JAMES McBRAYER GARVEY, OF NEW YORK, N. Y., ASSIGNOR TO THE AMERICAN
LAUNDRY MACHINERY COMPANY, OF CINCINNATI, OHIO, A CORPORATION OF
OHIO

LAUNDRY MARKING AND ASSORTING APPARATUS

Application filed May 18, 1928. Serial No. 278,769.

This invention relates to improvements in laundry marking and assorting apparatus. It is not practical in present day laundries to treat the laundry work of each customer separately, so that it is necessary to mark the various pieces of laundry so as to make it possible to bring together, after the laundry operation, the laundry work of each customer. It is therefore the present practice to assign to each customer a certain lot number, and to apply said lot number to each piece of laundry of said customer, which is usually done by applying thereto a suitable marker bearing said number. After the laundering of said pieces of work, during which time they are intermingled with the pieces of work of other customers, they are brought to an assorting room where the pieces of laundry of each customer are again brought together, the marker on each piece of laundry enabling this work to be accomplished.

The general object of the present invention is the provision of improved apparatus for marking and assorting laundry work, which apparatus embodies mechanism for easily and conveniently applying a suitable identifying marker to each piece of laundry work for enabling the assorting of the laundry work to be easily and quickly effected.

Further objects of the invention are in part obvious and in part will appear more in detail hereinafter.

In the drawings, which represent one suitable embodiment of the invention, Fig. 1 is a side elevation of a stapling machine for applying the identifying markers to the pieces of laundry work; Fig. 2 is an enlarged detail side view of the stapling head and frame member showing parts in vertical section; Fig. 3 is a detail horizontal view partly in plan and partly in section taken just above the anvil and guides for the tag moving mechanism; Fig. 4 is a detail sectional view on the line 4-4, Figs. 1 and 2; Fig. 5 is a perspective view of an assorting mechanism which may

be used in connection with the tag applying mechanism; Fig. 6 is a cross sectional view of said assorting apparatus on the line 6-6, Fig. 8; Fig. 7 is a similar view on the line 7-7, Fig. 5; Fig. 8 is a detail sectional view on the line 8-8, Fig. 5; Fig. 9 is a perspective view of one of the identifying markers having a piece of laundry attached thereto; and Fig. 10 is a bottom plan view of the forward end of the assorting mechanism shown in Fig. 5, the view being taken in the direction of the arrow D of Fig. 5.

The marking and assorting means includes a plurality of groups or series of laundry identifying markers, there being any desired number of markers in each group or series, say fifty, with the markers of each group or series of slightly different shape and bearing a different number from the markers of the other groups or series. A suitable magazine or holder is provided for the markers of each group or series, and each holder or magazine is so constructed that it will receive the markers of its own group or series and not those of any other group or series. Each holder or magazine is, of course, given the same identifying number as the markers which fit said holder or magazine.

In the present embodiment of the invention each magazine or holder is of rectangular form and comprises a top wall 1, side walls 2 and two bottom flanges 3 which extend upwardly and inwardly from the base of each side wall. Said flanges do not engage each other but a slot 4 is provided therebetween, as clearly indicated in Figs. 6 and 7. The two ends of each holder or magazine are closed by suitable wall members 5 and 6, each of which is provided with rearwardly extending flange portions 7 for suitable securement to the side walls 2. The front wall member or plate 5 is larger than the member 6 and its flanges 7 engage the outer walls of the magazine or holder. Suitably attached to the inner surface of the top wall of each holder or maga-

zine is a longitudinally extending spline 8, and the splines of the several holders or magazines are of different shape or are arranged in different locations on the inner surface of the top walls of the holders.

The identifying markers are formed from flat metal stock and remain in flat form without face projections of any kind. Each marker is provided in its upper edge with a suitable recess or cut-out portion 10 to receive or fit the spline 8 of one holder or magazine, and is provided in its two side edges with inwardly and upwardly extending slots 11 to receive the correspondingly bent flanges 3 of said holder or magazine and move freely along in the slot 4. Each marker is also provided near the bottom edge thereof with two spaced holes 12 adapted to receive a staple 13 by means of which said marker is secured to a piece of laundry work, as will later appear.

The bottom flanges 3 of each holder or magazine terminate a slight distance from the front wall 5, so as to provide a passageway 15 upwardly through which a marker may be inserted into a holder or magazine. If a marker is inserted into the wrong holder or magazine the marker recess 10 will not receive the holder spline 8, so that the marker will be prevented from being passed upwardly through the holder passageway 15 a sufficient amount to enable the marker slots 11 to receive the holder flanges 3 and will therefore be unsupported and remain in the hand of the operator. The operator then examines the tag and seeks out the proper holder to which it belongs when it may be inserted freely through the opening 15 and moved to the rear and be supported. If operators should insert a tag into the slot 4 at the bottom of the holder at a point other than the opening 15, and attempt to twist it into the supporting position, the sides of the tag will engage the flanges 3 and the entrance of these flanges in the slot 11 will be impossible.

At a suitable point on a wall or other similar support are a plurality of holder supports each comprising a face plate 16 and an outwardly projecting boss 17 having a core 18 which telescopes nicely into the rear end 50 of the holder 1 and against the flanges 7 of the rear plate 6. The upper wall of the holder is also provided with a suitable opening 19 adapted to receive the nose 20 of spring latch 21 mounted in suitable ears 22 forming a part of the plate 16. A suitable spring 23 serves to move this latch into latching position.

Each holder is further provided with a longitudinal slot 24 in one of its side walls 2 and this opening extends to the rear plate 6 and serves as a means for observing the tags in the holder. If desired, the edge of the side wall at this opening may be provided with suitable graduations 25 which will assist in

determining whether the holder is full and if not, just how many tags are missing.

The holder is still further provided at its outer or front end just back of the plate 5 with an opening 26 extending across the holder and of a width corresponding to the width of the marker and for use in discharging the markers from the rack or holder when applying them to the articles, as will appear.

The holders and tags thus far described are also capable of being used with a tag applying apparatus and this apparatus, generally speaking, is in the form of a stapling machine of any preferred type, such machines being available on the market. One of these machines is shown in Fig. 1 and it comprises a suitable frame 27 supporting a motor 28 driving through a belt 29 a suitable clutch 30 of any preferred type adapted for actuation by a rod 31 provided with a clevis and actuating the clutch to operate the stapling mechanism. The stapling mechanism is not shown in this case because it forms no part of the invention, it being sufficient that the machine will apply staples at the point indicated at 36. The staples applied at this point will have their side prongs 13', Fig. 4, bent over by the anvil indicated at 37, such anvils being old and part of the normal stapling machine.

The novel equipment applied to this stapling machine is the means for supporting the holders and for feeding the tags therefrom and in this arrangement the anvil 37 is continued back in the form of a supporting bed 38 supported by a suitable bracket 39 secured to the frame. Mounted on the rear end of this bed 38 are upper spaced slide guides 40 adapted to receive and guide a slide 41 provided with a pair of slide fingers 42 spaced apart and adapted, as will appear, to move a tag from the holder to the position indicated in dotted lines in Fig. 3, against a forward stop plate 43 secured in front of the anvil portion 37 and with the holes 12 of the tag in position below the prongs of the staple so that when an article is placed above the tag in this position the staple may be applied through the article and through the tag, as is indicated in Fig. 4, the position in this figure being one before the staple is actually applied. The tag is guided along the plate 38 and on to the anvil portion 37 by means of tag guides 44 similar in all respects to the slide guides 40. These guides, however, do not extend above the tag, but merely guide it by engagement with its side edges. Motion is transmitted to the slide 41 by a link 45 pivoted at 46 to another link 47 in turn pivoted at 48 to the frame. The two links 45 and 47 form a toggle which is broken upwardly, as shown in Fig. 1, when the slide is retracted to the rear, but, when straightened, move the slide forward and present the tag to its forward position under the stapling mechanism. The

link 47 is made in two parts and one is provided with a suitable pin 49 receiving a swivel block 50 through which an actuating rod 51 passes. This rod is surrounded by a spring 52 and is provided with a fixed collar 53 confining the spring between it and the swivel block 50 and therefore resulting in a pull upward upon the rod. The lower end of this rod is secured at 54 to the treadle 35.

Secured to a suitable bracket 56 back of the front head of the machine is a plunger cylinder 57 carrying a plunger 58 pressed downward by a spring 59. This plunger projects through the top of the cylinder and is there provided with a head 59' adapted for engagement by an arm 60 of a hand lever 61. The lower end of this plunger carries a suitable plug or block 62 adapted to fit in the end of the holder 1 and engaging the flanges 7 of the rear plate 6. The opposite or front plate 5 of the holder is adapted to seat in a suitable recess 63 formed in the bed 38 and the arrangement is such that the opening 26 in the top front end of the holder is presented in horizontal alignment with the fingers 42.

When the stapling machine is to be used on a lot of laundry work, the operator finds the proper holder with the proper identifying tags therein and places it with the front end plate 5 in the socket or recess 63 with the tag portions having the openings 12 toward the front of the machine. He then raises the plunger 58 by manipulating the hand lever 61 and causes the block 62 to engage in the upper or rear end of the holder when it will be firmly held in place. He is now ready to apply the tags to the articles. This is accomplished by placing an article in place above the anvil portion 37 and depressing the foot treadle until a tag is brought forward to the dotted line position shown in Fig. 3. This may be done before or after the article is placed above the anvil portion 37 of the bed 38. Further depression upon the treadle, after the tag has been brought in place, causes the clutch to be operated and the stapling mechanism to be set in operation when a staple will be applied to the article.

It is quite obvious that when the tag reaches its stopping point at the forward part of the machine, the treadle may be depressed to operate the clutch by reason of the lost motion provided in the spring 52, this spring also serving to hold the tag firmly in its forward position.

When the articles have been treated in the laundering or other process, the staples are removed by any suitable means and the articles loaded into a suitable container identified by other means for holding them together as a lot or group.

What I claim is:

A tag applying machine comprising a staple inserting mechanism having a work

support carrying an anvil and provided with a guideway through which tags may be fed to a position above the anvil, positioning means for a tag holder carrying a plurality of tags on said support at the opposite end of said guideway, means for clamping said tag holder down against said support, including a yielding block for engaging the rear end of said tag holder, and means for feeding tags through said guideway.

In testimony whereof I hereby affix my signature.

JAMES McBRYER GARVEY.
